Kammerdiner, Los Angeles, Calif.

Application January 7, 1929, Serial No. 330,921

7 Claims. (Cl. 255—27)

This invention has to do with a construction for well tools and it is a general object of the present invention to provide a jarring tool and various features of construction applicable to well tools in general.

In various well tools it is necessary, or advantageous, to provide constructions operable to yield or operate in certain manners under heavy strains or pressures, such constructions being commonly used in devices in which the heavy strains or pressures are suddenly released to perform operations through impact. For example, in jarring tools constructions are provided to receive heavy strains or forces and involve means which yield to the action of such forces to suddenly release them to cause violent jarring or hammering between suitably designed parts. Various conventional spring arrangements and hydraulic means have been proposed and used in tools of this character to yield gradually under the excessive strain in a manner to cause the releasing action at the desired time or when the desired strain has been reached. Considerable difficulty has been experienced, however, in obtaining spring construction which will adequately handle the heavy forces or pressures exerted in this type of equipment. Further, considerable difficulty has been experienced in tools of the character mentioned due to their general design and construction; for instance, the principal working parts have given trouble due to excessive wear and failure.

It is a general object of the present invention to provide a construction for well tools operable to yield under heavy strains in a manner to be useful in jarring tools, or the like.

The present invention provides a construction which will yield in a manner to allow only limited movement between members subject to heavy strain or pressure and offers far greater resistance than is offered by conventional spring arrangements.

Another object of the present invention is to provide various improved features of construction and arrangement of parts in a jarring tool. The present invention provides a tool which is of simple, inexpensive construction and which is effective and dependable in operation.

The various objects and features of the present invention will be best and more fully understood from the following detailed description of a typical form and application of the invention, throughout which description reference will be had to the accompanying drawings, in which:

Fig. 1 is a longitudinal detailed sectional view of a typical well tool embodying the present invention showing the parts in an unactuated position. Fig. 2 is a view similar to Fig. 1 showing the parts released or in operating position. Fig.

3 is an enlarged detailed view of a portion of the construction, being a view taken substantially as indicated by line 3—3 on Fig. 1. Fig. 4 is an enlarged detailed transverse sectional view taken as indicated by line 4—4 on Fig. 6. Fig. 5 is an enlarged detailed transverse sectional view taken as indicated by line 5—5 on Fig. 7. Fig. 6 is a side view of the construction being a view showing the outer part of the tool in section and the inner parts in elevation. Fig. 7 is a view similar to Fig. 6 showing the parts in the position similar to that shown in Fig. 2. Figs. 6 and 7 illustrate the parts in different rotative positions than shown in Figs. 1 and 2. Fig. 8 is an enlarged detail transverse sectional view taken as indicated by line 8—8 on Fig. 6. Fig. 9 is an enlarged detail sectional view taken as indicated by line 9—9 on Fig. 7. Fig. 10 is a vertical detailed sectional view of the central portion of the tool taken as indicated by line 10—10 on Fig. 4. Fig. 11 is a view similar to Fig. 10 taken as indicated by line 11—11 on Fig. 9. Fig. 12 is an enlarged top or plan view of one of the jaws. Fig. 13 is a side elevation of the jaw taken as indicated by line 13—13 on Fig. 12. Fig. 14 is an inside elevation of the upper portion of the key taken as indicated by line 14—14 on Fig. 12. Fig. 15 is an enlarged plan view of the key and ring, and Fig. 16 is an enlarged side elevation of the key and ring.

Certain features of the present invention are applicable, generally, to various well tools while other features of the invention are concerned more particularly with jarring tools such as are generally used in connection with fishing operations, that is, when fishing lost parts from wells. In setting forth the invention references will be had to a single well tool which may be considered a typical embodiment of the invention and which will serve to illustrate one manner in which the broader principles of the invention may be practically applied. Throughout the following detailed description reference will be had to a jarring tool and the various features of the invention will be described as applying to such tool, it being understood that such description is not to be construed as a limitation upon the invention as set forth in the appended claims.

The jarring tool illustrated in the accompanying drawings is designed to be used in connection with various equipment and tools, for instance, and is adapted to be used between a string of drill pipe 10, or the like, and a well tool 11, say, a fishing tool. The jarring tool provided by the invention is ordinarily inserted between the drill pipe 10 and the tool 11 used to engage the fish or part lost in the well. The present tool is designed to operate to cause upward jarring of the tool 11 from the drill pipe 10 upon applying an upward

strain or pull upon the drill pipe. The jarring action obtained by the present tool is intended to jar the fish or part engaged by the fishing tool 11 to dislodge it so that it can be withdrawn from the well. The details of the drill pipe 10 and the details of the various tools 11 that may be used in connection with the present device are of no particular concern in the present case, and therefore they have been omitted from the disclosure.

10 The tool which embodies the present invention includes, generally, an upper or outer section A, a lower or inner section B, jaws C operable through yielding means D to hold the sections A and B against relative movement, and control means E for the jaws C.

15 The tool illustrated in the drawings, being intended for use as a jarring tool, has one section adapted to be connected with the string of drill pipe 10 and the other section adapted to be connected with the tool or fishing device 11. The two main parts or sections A and B fit one within the other and in the preferred arrangement shown the outer section A connects with the drill pipe 10 while the inner section B connects with the tool 11.

20 The outer section A of the tool includes, generally, a tubular body 12, a coupling member 13 connected to the upper end of the body and serving as a connection between the body and the string of drill pipe 10, and a jarring member 14 at the lower end of the body 12. The tubular body 12 of the section A forms a casing or housing for various parts of the tool and is constructed to cooperate with the jaws C, as will be herein-after described. The coupling 13 is attached to the upper end of the body 12, for instance, it may be screw threaded into the upper end of the body, and is provided with a screw-threaded socket 15 to receive the pin 16 on the lower end of the drill pipe 10. The pin 16 may be the pin on the lower-most tool joint section of the drill pipe. The jarring member 14 is carried by the lower end of the body 12 and is provided to cooperate with a part of the section B, as will be herein-after described. In the construction illustrated the member 14 is slidably carried on a part of the section B and screw threads into the lower end of the body 12.

25 The inner section B includes, generally, a stem 17 which extends longitudinally through the body 12 of the section A, an extension 18 on the upper end of the stem cooperating with the coupling 13 of the section A, a head 19 at the lower end of the stem to cooperate with the jarring member 14, and an extension 20 below the head 19 extending through the jarring member 14 and provided with a threaded part 21 to carry the tool 11.

30 The stem 17 is an elongate part substantially smaller in diameter than the interior of the body 12 of the section A and extends centrally through the body 12 so that there is an annular space between it and the body, as shown through the drawings. This annular space carries the jaws C, means D, and the means E, as will be herein-after described. The stem 17 has a central longitudinal circulation opening 22 extending from one end to the other to conduct circulating fluid through the tool.

35 The extension 18 at the upper end of the stem 70 slidably fits packing means 23 provided in the coupling 13 and has a central longitudinal circulation opening 24 to conduct circulating fluid from the drill pipe 10 to the stem 17. In the construction shown the extension 18 is formed separate from the stem 17, being screw threaded to

the upper end of the stem, as clearly shown in Figs. 1 and 2 of the drawings.

40 The head 19 at the lower portion of the stem 17 is in the form of an enlargement on the stem, presenting an upwardly facing shoulder 27 and a downwardly facing shoulder 26. The downwardly facing shoulder 26 is adapted to cooperate with the upwardly facing shoulder 27 of the jarring member 14 of the section A. In Fig. 1 of the drawings these parts are shown separated or 10 in the unactuated position, whereas in Fig. 2 the parts are shown in active position with the shoulders 26 and 27 in cooperative engagement. The lower extension 20 of the section B projects downwardly from the head 19, being slidably carried 15 in an opening 28 formed through the jarring member 14. The threaded part 21, which carries the tool 11, is located below the jarring member 14.

45 With the construction above described, the sections A and B are connected or related for relative longitudinal movement between an unactuated position such as is shown in Fig. 1 and an actuated position such as is shown in Fig. 2. The upper extension 18 of the section B is related to 25 the coupling 13 to remain within the packing 23 during operation of the sections between these positions, and the lower extension 20 of the section B is related to the jarring member to allow free operation, as above described.

50 The jaws C are carried in the space between the body 12 of section A and the stem 17 of section B and are operable to form a releasable connection between the sections through the yielding means D. In the preferred arrangement there 30 are several jaws C, say, three jaws, symmetrically disposed around the axis of the tool. The outer parts of the jaws are provided with projecting parts or teeth 30 adapted to fit or extend into recesses 31 in the inner wall of the body 12 when the jaws are in the out or operating holding position as shown in Figs. 1, 4 and 6 of the drawings. The jaws are related or fitted in the space between the body 12 and the stem 17 so that they 40 can move inwardly from the position just described to a retracted or inoperative position where the teeth 30 are removed from the recesses 31, this position being illustrated in Figs. 2, 5 and 7 of the drawings.

55 In the preferred form of the invention each jaw is provided with several teeth spaced longitudinally of the jaw and the upper and lower ends 32 of the teeth are inclined or beveled as illustrated in the drawings. The recesses 31 are located in the inner wall of the body 12 to receive the teeth 30 when the parts are positioned as shown in Fig. 1. The upper and lower end walls 33 of the recesses are beveled to correspond to the ends 32 of the teeth. The beveling of the ends 32 and walls 33 of the teeth and recesses, respectively, causes the jaws to tend to move inwardly or toward the stem 17 from the position shown in Figs. 1, 4 and 6 when forces are applied 60 tending to move the jaws and body relative to each other longitudinal of the tool.

65 The yielding means D, through which the jaws C operate to control longitudinal movement between the members A and B, is designed to yield under great pressures or strains to allow a limited relative movement between the sections A and B while the jaws C remain in the out or active position with their teeth 30 seated in the recesses 31. In accordance with the present invention, the means D includes a plurality of superimposed plates 34 the adjoining faces of which do not 70

seat or fit together under normal conditions such as are shown in Figs. 1 and 3 of the drawings. In the form of the invention illustrated the plates are annular in their general configuration, being arranged around the stem 17 of section B to occur in the space between the stem 17 and the body 12. The adjoining faces of the plates 34 may be separated under normal conditions through various manners of forming the plates; for instance, the plates may be corrugated, crimped, or otherwise formed to act as herein-described. In the form of the invention illustrated, where the plates are annular in form, it is convenient to cup the plates making them slightly conical in configuration, as shown throughout the drawings. If cupped plates are arranged in adjoining relation, adjoining plates are reversed as to position, that is, one plate is arranged so that it faces up while the next adjoining plate faces down. In the case illustrated in the drawings I have arranged a flat plate between adjoining cupped plates. The plates 34 are preferably formed from heavy plates or sheets of material and may be tempered or otherwise treated to be sufficiently resilient to allow them to compress together as shown in Fig. 2 when sufficient compressive strain is applied.

In accordance with my invention I may provide a considerable number of plates 34 and arrange them so that the entire assembly or group of plates is subject to compression when the tool is operated by pulling upwardly on the section A. In the arrangement shown the plates 34 are arranged between a stop 35 provided on the stem 17 and a collar 36 which slidably fits the stem 17 and has a tubular extension 37 extending downwardly to engage the upper ends of the jaws C. The stop 35 may be screw threaded onto the stem 17 to be in fixed position on the stem.

40 The means D is such as to allow a limited amount of relative movement between the sections A and B while the jaws C are in cooperative engagement with the body 12, as shown in Figs. 1, 4 and 6. This relative movement allowed by the means D is utilized to cause the means E to release the jaws C from the expanded position shown in Figs. 1, 4 and 6 allowing them to collapse to the position shown in Figs. 2, 5 and 7. The plates 34 may be such as to seat 50 tightly together in allowing for the said relative movement between the sections A and B.

The means E which controls the jaws C, that is, which operates to releasably hold the jaws in the expanded position, includes key members 40 arranged between the adjoining vertical edges of the jaws. The keys 40 are shown carried by a ring 41 slidably carried on the stem 17 and normally yieldingly urged upwardly on the stem by a spring 42 which surrounds the stem and is under compression between the ring 41 and the shoulder 25 of the head 19. The upper ends of the key members 40 engage a stop 44 on the stem 17. The stop 44 shown is in the form of a collar screw threaded on the stem 17.

65 The key members 40 are designed to cooperate with the jaws C to hold them apart or in the expanded position illustrated in Figs. 1, 4 and 6 and to only allow the jaws to collapse or move to the "in" position shown in the other figures when the means D has been compressed allowing the section A to move upwardly relative to the section B so that the jaws C are moved vertically a predetermined amount relative to the key members 40. In the particular construction illustrated each key member 40 has spaced lugs

or projections 45 at its side edges adapted to engage the vertical end edges of the jaws C to hold the jaws out or apart, as shown in Figs. 1, 4 and 6.

5 The vertical end edges 46 of the jaws are provided with spaced recesses 47 designed to register with or receive the projections 45 when the jaws C have been moved vertically with the section A to a position such as is shown in Figs. 2, 5 and 7. The meshing of the key projections 45 and recesses 47 in the jaws C allows the jaws to move inwardly under the action of the beveled parts 32 and 33 above described. This disengages the jaws from the body 12 of section A allowing the body to move freely upward under the action of the upward pull being applied to it to cause compression of the means D. This upward movement of the section A relative to the section B is limited or stopped by the engagement of the jarring member 14 with the shoulder 26 10 of the head 19. It will be obvious that the sudden stopping of the upward movement of section A causes a severe jarring action on the section B.

15 In accordance with the preferred form of the invention, the upper and lower ends 48 of the key projections 45 are beveled as shown in Figs. 6, 7 and 16, while the upper and lower end walls 49 of the recesses 47 are correspondingly beveled so that the parts mesh together, as shown in Fig. 6, when the jaws C are in the "in" position. 20 The incline or bevel of the parts 48 and 49 causes the jaws C to be expanded to the "out" position by the action of the spring 42 when the body 12 returns to position where the recesses 31 are opposite the teeth 30. The various faces, edges, 25 etc., of the several parts may be shaped and finished as found most practical, for example the upper and lower outer corners of the jaws C, the lower end wall of the lower recess 31 etc., may be bevelled or rounded.

30 From the foregoing description it is believed that the operation of the device will be fully understood, it being apparent that upward pull on the body 12 when the parts are positioned as shown in Figs. 1, 4, 6 and 8 causes the jaws C 35 engaged with the body 12 through the cooperating parts or walls 32 and 33 to act on the plates 34 of the means D to compress them together. As the plates 34 compress the body 12 moves upwardly relative to the stem 17 of section B, 40 carrying the jaws C up with it. When the upward strain becomes sufficient, the plates will be compressed allowing the jaws to move relative to the key members 40 or stem 17 so that the recesses 47 register with and receive the projections 45. When the parts reach the position where the recesses 47 and projections 45 are opposite each other, the jaws move radially inwardly from the position shown in Figs. 1, 4, 6, 45 and 8 to the position shown in Figs. 2, 7, 5, and 9. 50 When the jaws C are thus collapsed or moved inwardly, the section A is released so that it is free to move upwardly relative to the section B. The section A moves freely upward relative to the section B until the jarring member 14 engages the head 19. 55 It will be apparent that the parts may be proportioned to allow any desired relative movement between the sections A and B between the time the section A is released and the jarring member 14 engages the head 19. 60

65 When the parts reach a position where the keys release the jaws allowing them to collapse, the means D operates to push the keys downwardly against the resistance of the spring 42. In Figs. 2 and 7 the parts are shown in position just before 70

the means D has acted to move the keys down. The spring 42 urges the keys upwardly so that they wedge between the jaws to spread them to the out position when the parts are positioned 5 with the recesses 31 opposite the teeth of the jaws.

The body 12 of the section A is related to the jaws C so that they are held in or prevented from expanding under the action of the spring 42 until 10 the body 12 has been located relative to the section B as shown in Fig. 1. When the parts reach this position, the tendency for the spring 42 to move the jaws C up causes cooperation between the beveled parts 48 and 49 so that the jaws C 15 move outwardly. As soon as the jaws C move outwardly or reach the expanded position, the key members 40 become positioned between the jaws C, as shown in Figs. 1, 4 and 6, locking the device in position ready for the next operation.

20 It is desired to call particular attention to the means D which operates to yield under pressure to allow a certain amount of relative movement between the sections A and B. Ordinary or conventional forms of spring means will not serve 25 in the means D, it being impossible to provide an ordinary spring means of sufficient resistance in the limited space available. The plate construction which I have provided may be designed to compress to allow the desired movement only 30 under heavy pressure or strain such as is required on the section A to get the necessary jarring action on the section B. In practice the plates 34 may be varied in number, shape and proportion to obtain the desired movement under 35 whatever strain or pressure is desired. For instance, by making the plates thin, or light, they will compress together allowing movement under less strain or pressure than will be necessary if they are made thick or heavy.

40 Having described only a typical preferred form of my invention, I do not wish to limit myself to the specific details set forth, but wish to reserve to myself any changes or variations that may appear to those skilled in the art or fall 45 within the scope of the following claims:

Having described my invention, I claim:

1. A well tool of the character described including, two sections related for limited relative longitudinal movement and having cooperating jarring shoulders, one section being adapted to be rigidly connected to a lost part in a well the other section being adapted to be attached to an operating string, a yielding assembly in one of the sections, and releasable means for transmitting force from one section to the other through said assembly releasable upon the assembly yielding a predetermined amount, the releasable means including an annular assembly including a plurality of cooperating jaws and keys.

60 2. A well tool of the character described including two sections related for limited relative longitudinal movement and having cooperating jarring shoulders, one section being adapted to be rigidly connected to a lost part in a well the other section being adapted to be attached to an operating string, a plurality of plates forming a compressible assembly engaging the first mentioned section, and means for transmitting force from the said other section to the first mentioned section through the plates and releasable to permit relative movement between the sections upon the plates yielding a predetermined amount and

means for transmitting force including an annular assembly including a plurality of cooperating jaws and keys.

3. A well tool for use in connection with a string of pipe, including, two sections connected for relative longitudinal movement, one section being adapted to be attached to the pipe to move therewith, and the other section being adapted to be attached to an object to be jarred, the sections having cooperating jarring shoulders, means releasably holding the sections against relative movement with the jarring shoulders apart, and a control whereby said means operates to release the sections upon a predetermined tensile strain being applied to the tool, said means including a series of jaws expandable to engage one section and said control including a shiftable member engaging the jaws and resilient means connecting said member and the other section.

4. A well tool including two sections connected for limited relative longitudinal movement and having cooperating jarring shoulders, means releasably holding the sections against relative movement with the jarring shoulders apart, and a control whereby said means operates to release the sections upon a predetermined force being applied to the tool, said means including a series of jaws expandable to engage one section, and said control including keys arranged between the jaws to hold them expanded, and resilient means connecting the keys and the other section.

5. A well tool including two relatively movable sections connected for limited relative longitudinal movement and having cooperating jarring shoulders, means releasably holding the sections against relative movement with the shoulders apart and a control whereby said means operates to release the sections under a predetermined force being applied to the tool tending to operate the sections to move the shoulders together, said means including spaced jaws expandable to engage one section and the control including a yieldingly supported key arranged between the jaws to hold them expanded.

6. A well tool including two sections connected for limited relative longitudinal movement and having cooperating jarring shoulders, means releasably holding the sections against relative movement with the shoulders apart, and a control whereby said means operates to release the sections under a predetermined force being applied to the tool tending to operate the sections to move the shoulders together, said means including a series of jaws expandable to engage one section and said control including a series of resilient plates acting between the jaws and the other section.

7. A well tool including two sections connected for limited relative longitudinal movement and having cooperating jarring shoulders, means releasably holding the sections against relative movement with the shoulders apart, and a control whereby said means operates to release the sections upon the application of a predetermined force tending to move the sections to bring the jarring shoulders together, said means including a series of jaws expandable to engage one section and said control including keys arranged between the jaws to hold them expanded, and a series of resilient plates connecting the keys and the other section.

MILLARD SUMTER BLACK.
